Primary Examiner — Manpreet S Matharu

Assistant Examiner — Keith J Wilson

(74) Attorney, Agent, or Firm — Jacobson Holman,
PLLC.(57) **CLAIM**

I claim the ornamental design for a container for dispensing liquids, as shown and described.

DESCRIPTION

FIG. 1 shows a front elevational view of a container for dispensing liquids;

FIG. 2 shows a bottom view of FIG. 1;

FIG. 3 shows a rear elevational view of FIG. 1;

FIG. 4 shows a right side elevational view of FIG. 1;

FIG. 5 shows a left side elevational view of FIG. 1;

FIG. 6 shows a top plan view of FIG. 1; and,

FIG. 7 shows a top perspective view of FIG. 1.

The broken lines illustrate portions of the container for dispensing liquids that form no part of the claimed design.
